JOHN McDONALD, OF NEW YORK, N. Y.

Letters Patent No. 83,394, dated October 27, 1868.

IMPROVEMENT IN BRICK-KILNS.

The Schedule referred to in these Letters Patent and making part of the same.

To all whom it may concern:

Be it known that I, JOHN McDONALD, of the city, county, and State of New York, have invented certain new and useful Improvements in Kilns for Burning Bricks; and I do hereby declare that the following is a full, clear, and exact description thereof, reference being had to the accompanying drawings, making part of this specification, in which—

Figure 1 is a side view of a section of the kiln; Figure 2, a longitudinal vertical section; and Figure 3, a cross vertical section.

The same letters indicate like parts in all the figures.

My said invention relates to improvements in kilns for burning bricks, described in and secured by Letters Patent granted to me, and bearing date, the 27th day of November, 1866.

In the accompanying drawings, A represents a long building, which I prefer to construct of brick, and consisting of two parallel side walls, *a a*, which, by preference, should be built double, with an air-space, *b*, in the middle. The kiln-space or tunnel B, between the two side walls, is covered by a double-arch roof, *c*, with an air-space, *d*, between the two arches. To avoid the necessity of making the side walls of great thickness, to resist the thrust of the arch-roof, strong iron rods, *e*, may be used to connect the two side walls at the base of the arch. The foundation, C, of this building should be made of strong mason-work, and I prefer to have it inclined, that the platforms or kiln-cars may descend by gravity. Both ends of this tunnel-like building are provided with doors, *f*, (only one shown in the drawings,) so that they can be readily opened and closed. Along the whole length, and extending for some distance beyond each end, are formed four (more or less) parallel tracks, consisting of rollers, *g*, mounted on suitable parallel rails, *h*, all in the same inclined plane.

A series of metallic quadrangular platforms, D, is formed of a width nearly equal to the width of the inside of the kiln or tunnel B. I prefer to make them square, although they may be longer or shorter than the width. Their front and rear edges should fit close.

The under surface of these platforms is to be provided with rails, *i i i i*, corresponding in number with the number of rows of rollers *g*, and either the lower surface of these rails should be grooved, to run on the rollers *g*, or the rollers should have their peripheries grooved, and the rails *i* made to fit them.

The sides of the platforms are made with downward-projecting flanches, *j j*, extending down below the upper surface of the rails *h* of the base or track, to run in sand, to be filled into the spaces *k k*, between the side walls of the kiln and the two outer rails, *h h*. The object of this is to permit cold air to circulate under the platforms D, to prevent them from being overheated, and to prevent the cold air from passing up into the kiln above the platforms. This will also have the effect of tempering the heat, which acts on the lower ranges of bricks on the platforms, and prevent them from being overburned. Such being the object, it will be obvious

that other and equivalent means may be substituted for the flanches *j j* running in sand; but I have described this as the best means, in my judgment.

Each platform is provided with a longitudinal cogged rack, *l*, about the middle of its width, the cogs of which are engaged by a pinion, *m*, on a horizontal shaft, *n*, which extends to the outside of the kiln, and there provided with a cog-wheel, *o*, engaged by a pinion, *p*, on a shaft, *q*, having crank-handle, *r*, by means of which the platforms can be moved along the tunnel. Two or more such mechanisms may be placed along the kiln.

And these platforms should either be made wedge-formed, that is, gradually thicker from their upper to their lower edges, so that, when resting on the roller-ways, their upper surface should be level, or, as the equivalent thereof, the upper surface of each platform may be made in the form of steps, as represented in fig. 4, as the object is to have the upper surface of each platform level, or composed of a series of level planes, that the bricks to be burned may be piled thereon properly; but if desired to dispense with the advantages due to the inclined base of the tunnel, the platforms can be made level, and they will then be made with their upper and lower surfaces parallel.

The bricks to be burned are stacked on each platform, as in an ordinary brick-kiln, as represented at E, with an archway, *S*, extending across, in which to build the fires; and the side walls *a a* are formed with apertures, corresponding with the archways *S*, and provided with doors, *S'*, to give access to fires. Other apertures, *t*, may be made through the side walls, near the top, through which to observe the progress of the burning, and these may be provided with doors, or may be closed up, when desired, by luting or otherwise.

There is a chimney, F, at the upper end of the kiln, and this chimney connects with the kiln at about the level with the upper surface of the platforms, that the heat may the more effectually act on the upper ranges of bricks.

In a kiln of about one hundred feet in length, the platforms D should be about five feet in length, and there should be about five archway-doors *S'* on each side, and their distance from centre to centre should be equal to the length of a platform, that the doors may correspond with the archways *S*; and in a kiln of such proportions the door nearest the upper end of the kiln should be distant therefrom about forty feet, and, as the chimney is at the upper end of the kiln, and the fires cannot be made in the archways until each platform in succession reaches the door nearest the upper end, the bricks on the platforms, between the upper end of the kiln and the platform opposite the first set of doors, will be gradually heated, by the heat from the fires in the several archways, as it passes on its way to the chimney; and at the lower or discharge-end of the kiln there will be a space of about thirty-five feet in length, without doors, that the bricks on the platforms, and passing the lower set of doors, may

be permitted gradually to cool down before they are discharged at the lower end.

After the kiln has been fairly started, and filled with platforms and stacks of bricks, so soon as the bricks on the platforms next to the discharge-end are in a suitable condition to be exposed to the atmosphere, the lower door is opened, the platform run out, the door closed, the whole series of platforms run down, the upper door opened, a fresh platform introduced, and the door closed.

As the baking progresses, and the platforms of baked bricks are discharged at one end, the stacks of fresh bricks introduced at the upper end are gradually dried and warmed up by the gentle heat in that part of the kiln beyond the upper set of doors, and by the time that they get to the upper doors, they are then in a condition to be safely subjected to a high heat. The fire can then be made in the archway, through the doors in the side walls; and as the platforms progress toward the discharge-end of the kiln, and so soon as it is observed that the bricks on a platform are sufficiently burned, the fire for that stack is permitted to burn out, or is extinguished, and the bricks gradually tempered, the heat being gradually less towards the discharge-end of the kiln. In this way the bricks, after being burned, are permitted to cool down gradually before being taken out of the kiln into the open air, as it is well known that if bricks are discharged into the open air at too high a temperature, they will crack and split.

The track on which the platforms or kiln-cars travel may be extended to any distance required from both ends of the tunnel, and such tracks may be formed on the upper surface of platform-cars running on lateral tracks, for the convenience of discharging the burned bricks where desired.

And, although I have above described the track as being formed of wheels, the platforms as being provided with rails to run on the roller-tracks, I do not wish to be understood as limiting myself to such, as it will be obvious that the platforms can be provided with wheels to run on a track of rails, and it will also be obvious that some of the advantages of my said invention can be availed of without the use of wheels, by sliding the platforms on ways.

What I claim as my invention, and desire to secure by Letters Patent, in kilns for burning bricks, is—

The tunnel or kiln, provided with a door at each end, and with a chimney, and with apertures through the side walls, for the management of the fires, substantially as described, in combination with movable platforms, on which the bricks to be burned are to be stacked, with archways in which the fires are to be made for burning the bricks, substantially as and for the purpose described.

JOHN McDONALD.
